(57) **CLAIM**

The ornamental design for a digital camera, as shown and described.

DESCRIPTION

FIG. 1 is a front perspective view of a digital camera, showing the new design;

FIG. 2 is a rear perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The broken lines showing the digital camera illustrate the environment of the claimed design and form no part thereof.

(Continued)

Dot-and-dash lines only indicate the boundary between the portion for which design registration is sought as a partial design, and other portions.
